UNITED STATES PATENT OFFICE.

JONATHAN B. WEST, OF ROCHESTER, ASSIGNOR TO L. N. ASIEL & CO. AND
BERTHOLD GALLAND, ALL OF NEW YORK, N. Y.

HOLDER FOR EMBROIDERY.

SPECIFICATION forming part of Letters Patent No. 340,265, dated April 20, 1886.

Application filed July 31, 1884. Serial No. 139,305. (No model.)

To all whom it may concern:

Be it known that I, JONATHAN B. WEST, of Rochester, in the county of Monroe and State of New York, have invented an Improvement 5 in Holders for Embroidery, Lace, &c., of which the following is a specification.

Embroidery, edgings, laces, &c., have been wound upon spools and placed in a cabinet or case to hold the same, as set forth in my application, Serial No. 109,655, filed October 22, 1883, and the strips of material have been passed out through openings and beneath guide bars or cleats upon the case, and pins have been provided to catch and hold the end 15 portions of such strips as they are wound up. These devices are also set forth in my aforesaid application, but in the same the spools were represented with tubular axes, and pins or rods passing through the same. Under some 20 circumstances it is difficult to withdraw the pins or rods for allowing of the removal of the spools.

My present invention is an improvement upon and modification of the aforesaid device, 25 whereby the spools will be held in place, but can easily be removed for the introduction of other or full spools. I make use of spools with pivot-pins projecting at their ends, and latches that are pivoted at the back part of the case 30 or cabinet, so that the latches are raised for the insertion or withdrawal of the spools, and are allowed to drop over and hold the pivot-pins in place after the spools have been inserted.

35 In the drawings, Figure 1 is a vertical section of a cabinet containing three ranges of spools. Fig. 2 is a sectional plan at the line *x x*. Fig. 3 is an elevation representing the pulleys and band for rotating the supporting 40 rollers and spools, and Fig. 4 is a detached view of the spool.

The case or cabinet is of suitable size, and may be more or less ornamental in construction. The bottom *A*, sides *B*, back *D*, and top 45 *E* are permanently connected. If the cabinet is to hold three ranges of spools, there will be two horizontal cross-pieces, *F*, forming ledges, and the bottom *A* projects at its front edge to the same extent as the ledges *F*, or a ledge, *F*, 50 is secured to the bottom *A*, as shown in Fig. 1.

There are rollers *g g* in pairs, each pair being adapted to receive one roller or range of rollers. Three pairs of these rollers are shown, and they have axes that pass into the side pieces, *B*, of the cabinet, and at one end these 55 axes project through and receive the pulleys *h*, around which the endless cord or belt *k* is passed, as seen in Fig. 3. The vertical part of such cord is in front of the strip *i*, and passes over the guide-pulleys *i* and through holes in 60 the said strip *i* to the respective pulleys *h*, so that the rollers are all revolved in the same direction when the cord is pulled down.

The rollers *g* support the spools *L*, the edges of such spools resting upon the rollers; hence 65 when the rollers are rotated the spools may be revolved by the frictional contact of the rollers, but those spools that are held by the strips of fabric being caught by the needle-points *o* are not moved by the rotation of the 70 rollers *g* beneath them.

Each spool *L* is made with circular heads *l*, of pasteboard or similar material, fastened to the ends of the axle *l*', and this axle should be of wood, and provided at each end with a projecting pivot-pin, *o'*, of wire, that pass through 75 the pasteboard heads and enter the axle.

The pivot-pins come end to end where there are two or more spools in a row, and these pins project, and there is sufficient distance between 80 the heads *l* for the latch-arms *n n*, that project from the back bar, *p*, which bar extends along the inner surface of the back of the cabinet, and is pivoted, so as to be swung sufficiently for raising the latch-arms *n* out of the way of 85 the pivot-pins *o'* when the spools are being inserted. It is preferable to support the back bar, *p*, by screws *z*, that pass loosely through holes in such back bar, so that the desired movement can be given to the back bar and 90 the projecting latch-arms. The latch-arm at one end of the back bar projects to the front of the case sufficiently to be used as a lever-handle, *r*, in raising or lowering the latch-arms.

95 The swinging front plates, *s*, are pivoted near their lower edges, so that they can be closed up into the front part of the case or cabinet, or swung down horizontally to open the case for the reception or removal of the 100

spools. These front plates are not as wide as the openings in the front; hence there are narrow spaces above the front plates for the strips of fabric to be passed out.

5 The bars *u* are provided for the fabric to pass beneath as it is drawn off, and there are the pins *o*, to catch the end of the fabric as soon as the same is drawn above the ledge *F* and falls against such pins; but instead of such 10 bars being in the form of cleats upon the case, as in aforesaid application, each bar extends from end to end of the front plate, and it is supported by the sheet-metal cap-pieces *v*, that are provided at the ends of the front plates, 15 and project therefrom at the places where the bars *u* are to be received and held.

Small nails are passed through the cap-pieces to secure them to the ends of the front plates and to secure the bars *u* in place.

20 I claim as my invention—
1. The combination, with the spools having

circular heads and projecting pivot-pins, of a case to receive the same, rollers to support and revolve such spools, and latches to hold the pivot-pins and spools while being rotated, substantially as set forth. 25

2. The cabinet-case having front plates pivoted near their lower edges, in combination with the pins *o*, the guide-bars *u*, and the end plates, *v*, for supporting the guide-bars *u*, substantially as specified. 30

3. The combination, with the cabinet-case and spools, of the latch-arms *n*, the back bar, *p*, and means for supporting the back bar and allowing it and the latch-arms to be moved, 35 substantially as set forth.

Signed by me this 17th day of July, A. D. 1884.

JONATHAN B. WEST.
